UNITED STATES PATENT OFFICE.

EUGENE WIET, OF SACRAMENTO, CALIFORNIA, ASSIGNOR TO WIET-GOETHE COMPANY, OF SACRAMENTO, CALIFORNIA, A CORPORATION.

TUBE-FORMING MACHINE.

No. 854,136.

Specification of Letters Patent.

Patented May 21, 1907.

Application filed February 12, 1906. Serial No. 300,741.

To all whom it may concern:

Be it known that I, EUGENE WIET, a citizen of the United States, and residing at 2500 Second street, in the city of Sacramento, county of Sacramento, and State of California, have invented certain new and useful Improvements in Tube-Forming Machines; and I do hereby declare the following to be a full, clear, and exact description of the said invention, such as will enable others skilled in the art to which it most nearly appertains to make, use, and practice the same:

This invention relates to improvements in machines for forming sheet metal tubes, and particularly tubes having a longitudinal seam.

The object of the invention is to simplify the operation of bending a strip of sheet metal, and interlocking the edges to form a continuous tube.

Broadly the invention consists of: a feed table from which a strip of sheet metal is drawn by feed rolls, and pushed between parallel plates with oppositely beveled edges; having bending rollers adjacent said beveled edges, to progressively roll the edges of the strip to conform to said bevel edges. A second set of feed rolls which push the strip between two dies respectively convex, and concave, and suspended one within the other to form a channel gradually tapering from a level plane inlet, to a "U" shaped outlet. A third set of feed rolls to receive the strip thus bent, and push it between curling rollers which progressively curl it over a mandrel to a tubular form with interlocked edges. And a set of ejection rolls which perfect the tube and eject it.

In the drawings: Figure: 1: is a side elevation of a machine constructed in accordance with this invention. Fig: 2: is a plan view from above of the same. Fig: 3: is an end view of the same. Fig: 4 5: 6: 7: are cross section details of the edge beveling rollers. Fig: 8: is a cross section detail of the bending dies. Fig: 9: 10: 11: 12: 13: 14: are details of the progressive curling and seam laying rollers. Fig: 15: 16: 17: 18: 19: are cross section enlarged details of the progressive stages of the tube bending; taken respectively at X¹ X², X³, X⁴, X⁵, Fig. 2. Fig. 20 is an enlarged side elevation partially in cross

section of the mandrel. Fig. 21 is a cross section of the same taken at X⁶.

In detail the construction consists of the frame composed of the pillar arches A, fixed at intervals on the struts A¹; A²; A³. The feed table B, is supported by the hangers B¹, clamped to the struts A¹; A². The feed table is provided with the laterally adjustable guides B², to control the strip A.

All of the feed rolls are in sets of two mounted in brackets M, fixed on the struts A¹; A². The bearings of the rolls are vertically adjustable in the brackets by means of the turn screws M¹, M² threaded in the cross plates M³. All of the feed rolls are driven by worms D¹, fixed on the main shaft D, and meshed with the gear D², fixed on the lower feed roll shaft, which in turn drives the upper roll through the meshed gears D³, D⁴. All of the feed rolls are driven from the same shaft, synchronized and timed to exert the same traction upon the strip to avoid any unequal, or buckling stresses.

The feed rolls C, C¹, take the strip from the feed table and push it between the parallel plates E¹, E², which are supported by the hangers E³, to which they are adjustably attached by the bolts, and set screws E⁴, E⁵. The outer edges of the said plates are beveled inwardly with respect to the strip. The rollers E⁶, E⁷, E⁸, E⁹, are fixed on the outer edge of each plate adjacent the beveled edge of the opposing plate; to progressively cause the edge of the strip to assume the angle of the bevel of the plate. The strip thus edged reaches the second feed rolls F, F¹, which, are provided with the annular grooves F³ to clear the bent edge of the strip. The function of these rolls is to push the strip between the dies G, G¹. These dies are supported adjustably by the bolts, and set screws G² G³ from the hangers G⁴, G⁵. The die G is concave and tapers from the plane width of strip, to a "U" shape at the delivery end. The die G¹, is convex in lines parallel to the concavity of the die G; within which it is supported. The strip thus bent reaches the third set of feed rolls H, H¹, which are respectively convex, and concave to conform to the present contour of the strip S. The function of these rolls is to push the strip between the rollers J¹; J²; J³; J⁴; J⁵; J⁶; J⁷; J⁸; J⁹; J¹⁰; which pro-

gressively curl the strip about the mandrel K, interlock the edges and lay the seam. The rollers J⁷; J⁸; J⁹; J¹⁰; adjustably mounted on the strut A³, support the strip and cause it to conform to the lower contour of the mandrel. The rollers J¹; J²; J³; progressively curl the edges of the strip inwardly until the oppositely bent edges overhang. The rollers J⁴; J⁵; progressively interlock the edges; and the roller J⁶, lays or compresses the seam against the mandrel, making it tight. To relieve the friction of the laying operation the mandrel is slotted and two antifriction rollers K¹, K², are inserted to take the compression of the roller J⁶. The tube thus formed reaches the fourth set of feed rollers L, L¹, which being the last are more properly called ejecting rolls. These rolls are both concave the upper being provided with the annular groove L³, to clear the seam of the tube. It is the function of these rolls to correct the distortions of the tube (if any due to the seaming operation, causing it to conform to the circle of the mandrel and to deliver the perfected tube from the machine.

The main driving shaft D, is hung in the bearings D⁵, fixed to the pillar arches A, and is suitably connected to the source of power.

Ordinarily the succeeding strip will push the strip ahead of it through the machine. It is advisable however to deliver the tube from the machine onto what is known as a draw table; consisting of an endless chain having suitable clamps to engage the end of the tube and pull it from the machine, if for any reason traction should prove insufficient to eject it.

Applicant is familiar with the art of seamless and welded drawn tubing, and of helical, and straight seamed, bent tubing. The advantages in the saving of waste material, labor, time, and the unlimited length of tubing possible are too obvious to require discussion. These advantages are the result primarily of the pushing of the tube through the machine instead of pulling, as has hitherto been the practice.

Having thus described this invention, what is claimed and desired to secure by Letters Patent is,

1. In a tube forming machine the combination with a frame and driving mechanism of a feed table of adjustable width, a set of adjustable feed rolls, and two adjustably spaced parallel plates with oppositely beveled edges with progressive bending rollers mounted adjacent said beveled edges; a second set of adjustable feed rolls, and a pair of dies respectively concave and convex, and adjustably suspended one within the other, forming a channel tapering from a flat plane to a "U" shape; a third set of adjustable feed rolls, and a series of progressive curling, and seaming rollers, coöperating with a mandrel; and a set of ejecting rolls synchronized with the before mentioned feed rolls.

2. In a tube forming machine the combination with a frame, and a driving mechanism of a feed table, a set of feed rolls, and parallel plates with beveled edges with rollers mounted adjacent said beveled edges; a second set of feed rolls, and a set of concave and convex dies suspended one within the other; a third set of feed rolls, and a series of progressive curling and seaming rollers coöperating with a mandrel; and a set of ejection rolls synchronized with the before mentioned feed rolls.

3. A tube forming machine comprising bending mechanism formed of parallel plates having bending rollers mounted adjacent their edges; curling dies suspended one within the other, and adjustable relative to each other, a mandrel, seaming rollers coöperating therewith, and means for pushing a strip of sheet metal successively through the bending, curling and seaming mechanisms.

In testimony whereof, I have hereunto set my hand this 29th day of January 1906.

EUGENE WIET.
